UNITED STATES PATENT OFFICE.

RETTA M. ULLERY, OF AURORA, ILLINOIS.

SURFACE ORNAMENTATION.

Application filed July 8, 1926. Serial No. 121,161.

This invention relates to new and useful improvements in surface ornamentations, and the invention is particularly adapted for use in connection with calendars and 5 postal cards.

The principal object of this invention is to provide in a surface ornamentation, a picture including a celestial body, such as the moon or sun, and simulating said body 10 by means of a coin, thereby producing a pictorial calendar or postal card which is especially adapted for use in connection with banks to constantly display before the depositor or the recipient of such a calendar 15 or postal card, the thought of saving money.

With these and other objects in view which will more fully appear the nature of the invention will be more clearly understood by following the description, the appended claims, and the several views illustrated in the accompanying drawings, in which—

Figure 1 is a view of a picture and mounting therefor embodying my invention, and 25

Figure 2 is a detail sectional view taken on the line 2—2 of Figure 1.

In the accompanying drawings, which illustrate one form of my invention, I have shown a surface ornamentation which includes a picture 5 mounted on a mat 6, the latter being provided with a backing sheet 30

7. The picture 5 is preferably an outdoor

picture and includes the representation of a celestial light giving body such as the sun or moon. In order to simulate a celestial 35 body and to provide a visible means indicative of saving money, I have provided a coin 8 which is mounted in a seat 9 formed conjointly in the picture 5 and mat 6.

The picture 5 is adapted, as above stated, 40 to be used in connection with calendars and postal cards, although it will be understood that the use of my invention is not limited thereto.

It is of course to be understood that the 45 details of structure and arrangements of parts may be variously changed and modified without departing from the spirit and scope of my invention.

I claim:

1. In a surface ornamentation, a picture including an exposed coin associated therewith for simulating a circular celestial body.

2. In a surface ornamentation, the combination with a mat and an exposed picture mounted thereon, the mat and picture being conjointly formed with a seat, and a coin mounted in said seat and cooperating with said picture for simulating a circular celestial body.

In testimony whereof I hereunto affix my signature,

RETTA M. ULLERY.
